UNITED STATES PATENT OFFICE.

WILLIAM G. HURLBERT, OF NILES, OHIO, ASSIGNOR TO THE BOSTWICK STEEL LATH COMPANY, OF NILES, OHIO, A CORPORATION OF OHIO.

METAL LATHING.

No. 900,019.

Specification of Letters Patent.

Patented Sept. 29, 1908.

Application filed May 28, 1908. Serial No. 435,538.

To all whom it may concern:

Be it known that I, WILLIAM G. HURLBERT, of Niles, in the county of Trumbull and State of Ohio, have invented certain new and useful Improvements in Metal Lathing; and I do hereby declare the following to be a full, clear, and exact description of the invention, such as will enable others skilled in the art to which it appertains to make and use the same.

The primary object of this invention is to provide a metal lathing of maximum strength and resistance, and increased anchoring capacity, and likewise one which may be readily secured in place.

The invention will be hereinafter fully set forth and particularly pointed out in the claims.

In the accompanying drawings, Figure 1 is a view in perspective. Fig. 2 is a longitudinal sectional view. Fig. 3 is a cross sectional view.

Heretofore the commercial form of metallic lathing in extensive use has been formed by striking up loops, in parallel rows, on one side of sheet metal, and in some instances the sheet as a whole has been strengthened by ridges or corrugations between and parallel with the several rows. It has been found, in practice, that the loops themselves are liable to be easily bent because of their inability to stand any considerable weight or pressure, and in some instances have failed to afford proper anchorage for the plaster. Furthermore workmen have found it more or less difficult to secure such lathing to studding by passing wires through the slits formed in producing the loops. All these objections are overcome by my improvement.

Referring to the drawings, the loops 1 are

all formed on one side of the sheet in parallel rows, preferably separated by ridges or corrugations 2. Each loop is anchored by bending or pinching inwardly its longitudinal sides, which are thereby, for a short distance, 45 made parallel to each other, such sides diverging at their ends. In thus forming each loop as a narrow arch the maximum of strength is secured, the lathing being capable of withstanding many times greater pressure 50 than when flat loops are used. Furthermore, additional anchorage for the mortar is thus obtained.

In arching the loops irregular openings are formed in the sheet on the opposite sides 55 of the loops thereof, such openings being widest at the centers of the loops, thus providing clear and unobstructed passages for binding wires. This in itself is a decided advantage, since with the ordinary slits difficulty is experienced in securing the lathing in place.

I claim as my invention:

1. A metal lath consisting of a sheet of metal having a series of loops projecting 65 therefrom, each loop being arched and having its sides bent toward each other.

2. A metal lath consisting of a sheet of metal having a series of loops projecting therefrom, each loop having its sides bent 70 substantially parallel with each other at the center of the loop.

In testimony whereof, I have signed this specification in the presence of two subscribing witnesses.

WILLIAM G. HURLBERT.
